UNITED STATES PATENT OFFICE.

WILLIAM H. ALLEN, OF DETROIT, MICHIGAN.

POWDER FOR REDUCING IRRITATION.

No Drawing.

Application filed July 28, 1922. Serial No. 578,232.

To all whom it may concern:

Be it known that I, WILLIAM H. ALLEN, a citizen of the United States, and residing at Detroit, in the county of Wayne and State of Michigan, have invented a new and Improved Powder for Reducing Irritation, of which the following is a specification.

This invention relates to means for preventing chafing and for reducing irritation 10 of human skin caused by perspiration and the friction of clothes upon the moist surfaces, and its object is to provide means to convert the dead adherent epithelial débris into compounds that are not readily broken 15 down by bacteria.

Where chafing has begun, the healing of the skin is delayed and the irritation increased in many persons through the growth of bacteria in the dead adherent tissue, and 20 it has been found that by checking or stopping this bacterial action, the natural fluids in the skin soon reconstruct the chafed surfaces.

When the dead adherent tissue at the 25 chafed surfaces of the human body is tanned, especially by means of chromium salts, bacterial action is practically stopped, and furthermore, the chafed surfaces heal almost immediately. The tanning material must 30 be applied in minute quantities and preferably dry.

To carry this invention into effect, a finely powdered inert mineral substance such as 35 hydrated magnesium silicate or talc is moistened with a solution of a chromium salt, basic chromium sulphate preferred, ($\text{Cr}_2(\text{SO}_4)_3(\text{OH})_6$), the proportions being such that after the mixture has dried it will comprise about five per cent of this chromium 40 sulphate, although this percentage may be increased or diminished. Each particle of the talc is thus coated with a film of the chromium salt. I prefer this to mixing the powdered talc with the powdered salt, as 45 this dry mixture is liable to contain more or less broken fragments of the salt which

are liable to be irritating to the skin. Care must be taken that the mineral powder contains nothing that could irritate the skin or combine with the chromium salt to produce 50 an irritant. The dried powder is dusted or rubbed onto the chafed or irritated surface and it usually brings immediate relief. It is not to be considered a remedy for skin 55 diseases.

While I prefer basic chromium sulphate as giving the best results, any other normal or basic water soluble salt of chromium may be used with beneficial results, including chlorides, acetates and the other sulphates. 60 Any other mineral substance which can be finely powdered and which will be inert in a solution of a chromium salt may be employed instead of talc, clays being a good example, but because of its peculiar softness 65 and color, talc is preferred.

The proportions and combinations may therefore be varied by those skilled in the art without departing from the spirit of my invention as set forth in the following 70 claims.

I claim:

1. The process of preparing a powder for reducing the irritation of human skin, which consists in moistening powdered talc with a 75 solution of basic chromium sulphate and then drying the mixture, the amount of chromium salt in the dried mixture being about five per cent of the whole.

2. The process of preparing a powder for reducing the irritation of human skin which consists in moistening powdered inert mineral substances with an aqueous solution of a chromium salt, and then drying the mixture. 80

3. An admixture of a soluble chromium sulphate and a powdered inert silicate.

4. Powdered talc having its particles covered with a film of soluble chromium sulphate. 85

WILLIAM H. ALLEN.
